UNITED STATES PATENT OFFICE.

DAVID W. BUNDY, OF TORONTO, ONTARIO, CANADA.

PAY DEVICE.

SPECIFICATION forming part of Letters Patent No. 390,342, dated October 2, 1888.

Application filed January 31, 1888. Serial No. 262,570. (No model.)

To all whom it may concern:

Be it known that I, DAVID W. BUNDY, of Toronto, in the county of York, Province of Ontario and Dominion of Canada, have invented a new and useful Improvement in Pay Devices, of which the following is a full, clear, and exact description.

This invention relates to an improved device for use in paying off the employés of business establishments; and it has for its object to facilitate the distribution of the proper payments and to provide against the accidental or designed receipt by any employé of the payment due another.

15 The invention consists, mainly, of a tray provided with series of pockets, each bearing the name and numerical designation of an employé, and a number of money-boxes adapted for reception in the pockets and each bearing 20 the number of its respective pocket, all arranged for use as hereinafter described.

The invention also comprises certain other novel features, hereinafter fully described, and pointed out in the claims.

25 Reference is to be had to the accompanying drawings, forming a part of this specification, in which similar letters of reference indicate corresponding parts in both the figures.

Figure 1 is a perspective view of a pay device embodying my improvement arranged for use, parts being shown removed therefrom. Fig. 2 is a longitudinal sectional view of the said device arranged for transportation.

The device taken to illustrate my invention 35 comprises a deep tray, A, which is divided by transverse partitions B and longitudinal partitions C into series of like pockets, D.

Each pocket is constructed to receive a flat money-box, E, having a laterally-opening 40 hinged lid, F, endwise, so that the box will be held closed when contained therein, and the pocket is of such depth that the box, when fully seated therein, will project somewhat from the mouth of the pocket, so as to render 45 the removal of the box perfectly convenient.

The partitions B are, by preference, made considerably thicker than the partitions C, and at the side of each pocket D bear the numeral, G, designating, and immediately beneath the same a label, H, bearing the name 50 of, the employé for whom the said pocket is

intended. Each box E has on the outside of both ends and on the interior of the hinged lid F or the box a number, produced by stamping or otherwise, corresponding to that on 55 the pocket in which it is received, each employé being apportioned a pocket, D, bearing his name and the number by which he is, for convenience, designated, and a corresponding money-box E. In paying off, the boxes are 60 removed from the tray and in them placed the amounts due the employés designated by the corresponding numerals. The number on the interior of the lid F or box conveniently serves to indicate to the user the box that is being 65 filled, and, the same number being on both ends, whichever end is introduced into the pocket the designation of the box is clearly apparent. A cover, J, which is entirely removable, is provided for the tray, and is of 70 such height interiorly as to easily accommodate the projecting ends of the boxes, while securely retaining them in their respective pockets. Handles K are also provided on the tray for convenience in carrying.

To each end of the tray is pivoted a bracket-piece, L, which can be folded within the limits of the tray or adjusted to project forward from the same, as shown in Fig. 1, so as to hold the tray in a forwardly-inclined position 85 to enable the characters on the tray and boxes to be more readily observed. A segmental slot, M, is formed in each bracket-piece to receive the shank of a set-screw, N, held in the end of the tray, so that the bracket-pieces can 85 be locked in any position to which they may be adjusted.

The distribution of the boxes containing the pay to the employés as they come up in order is thus rendered extremely convenient, and 90 the names on the pockets serve as a check against the distributor accidentally giving a box to the wrong person or an employé designedly obtaining another's box.

The emptied boxes can be deposited in a 95 common receptacle for collection and replacement in the tray.

The name on any pocket can be readily changed for a new employé by applying a new label bearing the latter's name over the 100 first.

Having thus described my invention, what I

claim as new, and desire to secure by Letters Patent, is—

1. A pay device consisting of a tray provided with series of pockets, each bearing both the name and the numerical designation of an employé, and a number of money-boxes adapted for reception in the pockets and each bearing the number of its respective pocket, substantially as described.
- 10 2. A pay device consisting of a tray provided with series of pockets, and a number of marked money-boxes provided with laterally-opening lids, adapted to be received endwise in the pockets and to fit closely between and be held closed by the walls of the same, substantially as described.
- 20 3. In a pay device, the combination, with a tray having pockets for the reception of pay boxes or receptacles, of adjustable brackets on the ends of the tray adapted to fold within the limits of the tray or to project therefrom, so

as to support the tray in an inclined position, and means for locking the brackets in position, substantially as described.

4. In a pay device, a tray provided with series of pockets separated by partitions, the partition at the side of each pocket bearing a numeral, and adjacent thereto a label having a name marked thereon, substantially as described. 25

5. A pay device consisting of a tray formed with series of pockets, a number of marked money-boxes adapted for reception in, but to project from, the mouths of the pockets, and an entirely-removable cover arranged to set 30 down over the boxes upon the tray and to hold the boxes in place, substantially as described. 35
